UNITED STATES PATENT OFFICE.

COMFORT A. ADAMS, OF CAMBRIDGE, MASSACHUSETTS, ASSIGNOR OF ONE-HALF TO
FRANCIS S. MARDEN, OF NORFOLK, CONNECTICUT.

COMMUTATOR.

Application filed August 19, 1916, Serial No. 115,768. Renewed January 25, 1923.

To all whom it may concern:

Be it known that I, COMFORT A. ADAMS, a citizen of the United States, and resident of Cambridge, in the county of Middlesex, State of Massachusetts, have invented certain new and useful Improvements in Commutators; and I do hereby declare the following to be a full, clear, and exact description of the invention, such as will enable others skilled in the art to which it appertains to make and use the same.

This invention relates to circuit controlling means for electric hammers or similar tools. The invention is directed more particularly to the provision of means for energizing the operating coils of the hammer at predetermined time intervals and to a suitable degree, the coils being alternately energized and deenergized so that the plunger or reciprocating element of the hammer may be made to strike a succession of rapid blows on the tool or its carrier.

It is an object of the invention to provide a commutator by which the coils of the hammer will be alternately energized and deenergized without opening their circuits. This result is attained by establishing a shunt circuit first about one coil and then about the other so that only one coil is at any time completely energized. The arrangement is such that comparatively heavy currents may be used and the inductance of each coil may be utilized in turn to help build up the magnetic field of the other coil.

Another object of the invention is to control the strength of the hammer blows by controlling the energizing current as by a rheostat in the supply circuit. The frequency of the blows may also be controlled by a rheostat which controls the speed of the motor that drives the commutator.

The invention also provides a commutator of inexpensive, simple and compact construction which may be easily carried about from place to place and connected to a source of current supply at any convenient location with respect to the work being performed by the hammer. The construction has the further advantage that the hammer may be connected to the commutator without regard to polarities thereby rendering it unnecessary for the operator to have any considerable knowledge of the electrical arrangement.

The invention also embraces numerous

other features and advantages which will be better understood by reference to the following description, taken in conjunction with the accompanying drawings showing the preferred embodiment of the invention. In the drawings

Figure 1 is a side elevation, with the cover portion of the apparatus shown in section;

Fig. 2 is a plan view of the apparatus with the cover portion removed;

Fig. 3 is a view in section taken along the line 3—3 of Fig. 1;

Fig. 4 is a plan section through the commutator along the line 4—4 of Fig. 1;

Fig. 5 is a view showing, partly in section, the shaft of the apparatus and one of the slip rings with its corresponding brush supporting binding post; and

Fig. 6 is a simplified diagram of the circuit connections of the commutator and a hammer associated therewith.

Referring to the drawings in which similar reference characters denote similar parts throughout the several views thereof, 10 is a base made preferably of aluminum and formed with a chamber within which certain parts of the apparatus may be mounted. The base is provided with a removable bottom plate 11. To the top of the base is attached in any convenient manner a motor 12 for driving the commutator. The bearing 13 at the outer end of the motor is provided with a rod 14. A similar rod 15 is attached to the top of the base at the other end of the apparatus. These rods serve to hold in place the cover 16 which is provided with apertures through which the rods extend. Clamping nuts 17 retain the cover in place. The whole apparatus may then be conveniently carried by means of the handle 18. The cover 16 may be provided with ventilation holes 19 as desired.

The shaft of the motor is extended as at 20 to a ball bearing 21 on a supporting column 22 attached to the other end of the base 10. A ventilating fan 23 may be mounted on the shaft 20 between the motor and the commutator.

The commutator comprises an insulating disk 24 fastened to the shaft 20 and carrying upon its periphery a pair of conducting segments 25 and 26 separated from each other at points 40. On either side of the disk and segments are smaller insulating disks 27 and 28 fastened to the shaft 20.

Each of these disks 27 and 28 is surrounded by a collector or slip ring 29 and 30 respectively. The conducting segment 25 is connected to slip ring 29 by a connector bar 31, (Fig. 4). A similar connector bar 32 completes the circuit between conducting segment 26 and slip ring 30. Beside the disk carrying the segments 25 and 26 is a brush holder comprising a frame 33 having a bearing portion 34 through which passes a shaft 35 supported in brackets 36 attached to but insulated from the base 10. Springs 37 wound about the shaft 35 and fastened at one end to the brackets 36 and at the other 10 ends to the frame 33 maintain the brush against the surface of the segments of the commutator. The frame 33 is provided with a cross-bar 38 upon which a brush 39, preferably of carbon, is supported. As 15 shown most clearly in Fig. 3, the brush 39 is narrower than the gaps 40 between the conducting segments 25 and 26. To prevent the brush from dropping into the gaps as they pass by the brush insulating bridges 41 20 and 42 are provided at the ends of the gaps. The bridges are made narrow to reduce friction between them and the brush. Instead of being made of insulating material they may be made of metal with insulating 25 strips between their ends and the ends of the conducting segments. While the arrangement illustrated is the preferred one, the bridges may be omitted and the brush holder may be provided with an insulating spacing 30 block which, with the brush itself, will be of sufficient width to bridge the gaps and thus prevent the brush from dropping into the latter. The brush is clamped in place by a screw 43 which also retains the spacing block 35 35 if one is used. Under certain conditions a brush formed of a conducting member wide enough to bridge the gaps 40 may be substituted for the narrow brush 39 illustrated in the drawing. While the brush holder is 40 insulated from the base, provision is made for connecting to the holder a wire which forms part of the circuit connections of the apparatus. This may be accomplished in any well known manner.

50 Two binding posts 44 and 45, each insulated from the base, are adapted to be connected to wires passing through the top of the base. Each of these binding posts is formed with an eye at the top for the purpose of retaining brushes 46 and 47 in place by means of screws 48 and 49, the brushes being formed with flexible extensions adapted to engage the slip rings 29 and 30 respectively.

55 Within the chamber in the base of the apparatus may be mounted a quick break and non-arcing switch for controlling the supply circuit. This switch is designated 51 in the wiring diagram, Fig. 6, and its operating handle is shown at 52 in Fig. 2. Within the

chamber in the base is also mounted a rheostat 53 for controlling the current supplied to the armature 54 of the motor. Instead of controlling the motor through its armature it may be controlled through its field in 70 the usual manner. This rheostat may be of any desired construction and is provided on the outside of the base with an operating button 55 and a dial 56 which has an indicating mark traveling adjacent to a fixed 75 scale 57 graduated according to the degrees of speed attainable by the motor. As shown in Fig. 6 the field 58 of the motor is connected directly across the supply conductors. A fixed resistance 60 is also mounted within 80 the chamber in the base and in series with this fixed resistance is a rheostat 61 for varying the strength of the hammer blows. This rheostat 61 may be of any desired construction and is operated by a button 62 upon the outside of the base. Like the rheostat of the motor it is provided with an indicating dial 63 and a scale 64 graduated to represent various intensities of the hammer blow. The base may be provided with any desired 85 number of ventilating apertures 65. Almost all of the wiring of the apparatus is contained within the chamber in the base. For the purpose of connecting supply leads to the apparatus the base is provided with 90 a pair of sockets 66 which may conveniently be mounted in an insulating plate set in an aperture at one end of the base.

A corresponding arrangement of three 95 sockets 67 at the other end of the base provides for the connection of the hammer leads to the apparatus.

Referring particularly to the wiring diagram of Fig. 6, main conductors 68 and 69 within the base are connected to the terminals of the sockets 66. 68 leads directly to one terminal of the fixed resistance 60 while 105 69 leads to one terminal of the switch 51. From the other terminal of the switch a conductor 70 leads to one of the end sockets 67. 110 The field 58 of the motor and its armature 54 and controlling rheostat 53 are mounted in parallel between conductors 68 and 70. A conductor 71 connects the other end socket 67 to the rheostat 61 which is connected in 115 series with the fixed resistance 60 and the conductor 68. The middle socket of the group 67 is connected by wire 72 to the brush holder frame 33, this wire passing through the base of the apparatus and being connected to this frame in any convenient manner, as previously referred to. The binding post 45 is connected to conductor 70 by wire 73 while the binding post 44 is connected to the conductor 71 by a wire 74.

The hammer shown diagrammatically in Fig. 6 may be of any construction. It comprises a striking coil 75 and a lifting coil 76 from the outer ends of which conductors lead to plugs adapted to fit into the sockets 120

67. The common or mid connection of the coils is connected to one terminal 77 of a switch, the other terminal 78 of which is connected to a lead running to a plug which engages the middle one of the sockets 67. The switch is controlled by an operating handle 79 mounted near the handle 80 of the hammer. The striking plunger 81 of the hammer is shown in its rear position where it engages an impact member 82 between which and the end of the hammer casing there is a spring 83. The other details of construction of the hammer need not be described since they form no part of the present invention.

In the operation of the apparatus, a supply line from any appropriate source of current is connected to the sockets 66. Switch 51 is closed and the motor speed adjusted to the proper degree by a manipulation of the resistance 53. The plugs on the hammer leads are connected to the sockets 67 and it will be seen that it is immaterial how the end plugs and sockets are connected, it being only necessary for the operator to make sure that the middle plug is in the middle socket. Assuming that the commutator is in the position shown, in which the brush 39 is in contact with neither of the conducting segments 25 or 26, then both of the coils 75, 76 of the hammer will be connected in series across the supply means and as they are opposing each other in their effect there will be no motion of the striking plunger. If now the commutator is moved in the direction of the arrow of Fig. 6 so that the brush 39 engages conducting segment 26, a short circuit or shunt will be established about the coil 75 of the hammer but the coil 76 will be energized by current which passes over conductor 68 through the resistance 60, rheostat 61, conductor 71 and hammer lead, coil 76, switch 77-78, the central hammer lead, conductor 72, brush 39, segment 26, slip ring 30, brush 47, binding post 45, conductor 73, switch 51 and conductor 69 to the other supply lead. Coil 76 will thus be energized to lift the striking plunger and hold it so long as current continues to flow through the coil. At the instant the conducting segment 26 leaves the brush 39 the return path through the conductor 72 will be broken and the self-induction of the coil 76 will cause a discharge from the latter back through the line. Since the circuit is open at the brush 39 the inductive discharge or kick of coil 76 will pass through coil 75. This discharge will be in such a direction through 75 as will tend to produce a polarity like that which will be produced when, an instant later, the brush 39 makes contact with the segment 25 of the commutator establishing a short circuit or shunt about the coil 76 and causing coil 75 to be energized over the following path: conductor 68, resistance 60, rheo-

stat 61, conductor 74, brush 46, slip ring 29, segment 25, brush 39, wire 72, middle hammer lead, switch 77-78, coil 75, outer hammer lead back to wire 70, switch 51, wire 69 to the supply lead. Current will at this instant be flowing through coil 75 in the same direction as the inductive discharge from the coil 76 and will persist as long as the brush 39 is in contact with segment 25. At the instant the brush passes off of this segment the coil 75 will discharge or kick through the coil 76 and the polarity produced by this inductive current will be the same as that produced by the main current in this same coil when at the next instant the coil 75 is short circuited. These operations will be repeated so long as the apparatus is in operation. The inductance of each coil is as above explained, used to help build up the current in the other coil so that instead of wasting all of the electro-kinetic energy of the current in one coil in heat and delivering a new supply to the other coil, a part of this energy is transferred directly to the second coil with an accompanying increase in the rate of decrease of current in the first coil and in the rate of increase of current in the latter coil. This is an important feature of the invention as it means an increase in the aggregate energy delivered to the plunger during each stroke, particularly for high speeds of the commutator.

By a proper timing of the interval at which each coil is short circuited, the apparatus can be adjusted so that the short circuit is established about the coil 76 at substantially the instant that the striking plunger begins to rebound from the impact member 82 at the handle end of the hammer. The effect of the coil 75 will at this instant become appreciable and tend to attract the striking plunger just as it is moving in the same direction on the rebound. This is a further advantage of the present construction as it renders a maximum effect to the blow upon the tool. The proper timing of the apparatus is effected by means of the controlling rheostat 53.

As the energizing circuits have been traced above, it will be seen that the rheostat 61 is always present in the energizing circuit of each coil so that it has the same effect on the degree of energization of each coil. It therefore is immaterial which way the hammer leads are connected to the sockets 67 so long as the middle plug is in the middle socket.

While the resistance 60 has been referred to as a fixed resistance it will be understood that throughout the majority of operations of the apparatus this resistance will be of a predetermined magnitude, but of course may be changed from time to time, or even entirely eliminated if desired. The function of this resistance is to prevent a

dead short circuit between the line conductors if for any reason, due to some abnormal condition, the arc or spark between the brush 39 and the commutator segments 25 and 26 should be drawn completely across the gap between these segments, in which case the line would be short circuited by an arc of very low resistance. The fixed resistance is therefore inserted as an extra safe-
guard, although it has been found in practice that the apparatus may be properly operated without any such resistance in circuit. The resistance is also helpful as its presence reduces the time constant of the circuit including the hammer coils and hence reduces the time required for the current to build up in these coils. Instead of using a narrow brush 39 as illustrated, it is possible to operate the apparatus by using a brush of a width that will bridge the gap between the segments of the commutator. In this case the inductive kick of each coil as the brush passes from one segment to the other will take place through the brush and the two segments in parallel instead of through the other coil. While the apparatus operates successfully under these conditions the arrangement first described is preferred.

Various modifications or changes in the details of construction of my invention may be made without departing from the principle thereof.

I claim:

1. A system of the character described, comprising a source of current, a pair of coils connected together, main conductors connecting the coils in series with the source, a magnetizable plunger within the coils, a common conductor leading from the point of connection of the coils, a contact member to which the common conductor is connected, a pair of movable conducting members adapted to engage the contact member alternately, a pair of movable conducting members, each electrically connected to one of the first-named conducting members, a fixed contact member engaging each of the last-named movable contact members, and conductors connecting the last-named fixed contact members to the main conductors.

2. A system of the character described, comprising a source of current, a pair of coils connected together, main conductors connecting the coils in series with the source, a magnetizable plunger within the coils, a common conductor leading from the point of connection of the coils, a fixed contact member to which the common conductor is connected, a pair of rotary arcuate conducting members adapted to engage the fixed contact member alternately, insulating members between the ends of the arcuate conducting members, said insulating members being wider than the fixed contact member, so that the latter is out of engage-

ment with the arcuate members for an appreciable interval of time during the rotation of these members, a pair of circular conducting members adapted to rotate with the arcuate conducting members, and each electrically connected to one of said arcuate members, a fixed contact member engaging each of the circular conducting members, and conductors connecting the last-named fixed contact members to the main conductors.

3. A system of the character described, comprising a source of current, a pair of coils connected together, main conductors connecting the coils in series with the source, a magnetizable plunger within the coils, a common conductor leading from the point of connection of the coils, a fixed contact member connected to each of the main conductors, movable contact members adapted to engage each of the fixed contact members, a pair of movable contact members, each electrically connected to one of the first-named movable contact members, insulating members between the ends of the pair of movable contact members, a fixed contact member connected to the common conductor and adapted to be engaged successively by the pair of movable contact members to establish a short-circuit about each of the coils alternately, said last-named fixed contact member being of lesser width than the insulating members, so that an interval of time occurs between the establishment of each short-circuit to permit inductive discharge of the non-short-circuit coil through the other coil.

4. The combination with an electric hammer having a pair of windings operating on a magnetizable plunger, of a circuit controller therefor for permitting the energization of said windings alternately, said controller comprising a pair of conducting segments, a brush common to both said windings engaging said segments alternately, a pair of collector rings each having electric connection with one of said segments, a brush for each collector ring, a supply circuit for energizing said windings, one conductor of said circuit being connected to one winding, the other to the other winding, connections between the brush of one collector ring and one conductor and from the brush of the other collector ring to the other conductor, means for rotating the segments and collector rings, and means for controlling the speed of said rotating means.

5. A system of the character described, comprising a pair of coils, a magnetizable plunger adapted to be reciprocated by a current in said coils, an impact member against which said plunger strikes when attracted by one of said coils, means for establishing a short circuit about each of said coils alternately in order to permit the other coil to

attract said plunger, and means for controlling said short circuiting means to cause the same to establish the short circuit about the coil which attracts said plunger against 5 said impact member at the instant when said plunger rebounds from said member.

6. A system of the character described, comprising a striking coil and a lifting coil, a magnetizable plunger adapted to be reciprocated by said coils, an impact member against which said plunger strikes when attracted by said lifting coil, a source of current connected to said coils, means for establishing a short circuit about said striking coil in order that said plunger may be 10 attracted by said lifting coil and for thereafter establishing a short circuit about said lifting coil at the instant when said plunger rebounds from said impact member in order 15 that said striking coil may then be effective to attract said plunger.

7. The method of operating an electric

tool having a striking coil, a lifting coil, a magnetizable plunger adapted to be reciprocated by the coils, and a member to take up the impact of the plunger when attracted by the lifting coil, which consists in supplying a continuous electric current to the terminals of the coils, establishing a short-circuit about the striking coil for a predetermined period of time, breaking the short-circuit about the striking coil to permit the inductive discharge of the lifting coil to discharge through the striking coil, establishing a short-circuit about the lifting coil 25 while the discharge from the lifting coil has an appreciable value and while the plunger is rebounding from the impact member, and maintaining the short-circuit about the lifting coil for a predetermined 30 period to permit the striking coil to attract the plunger. 35

In testimony whereof I affix my signature.
COMFORT A. ADAMS.
